UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

AIR-GUN.

1,286,359.

Specification of Letters Patent.

Patented Dec. 3, 1918.

Application filed April 15, 1918. Serial No. 228,607.

To all whom it may concern:

Be it known that I, CHARLES F. LEFEVER, a citizen of the United States of America, residing at Plymouth, in the county of Wayne and State of Michigan, have invented certain new and useful Improvements in Air-Guns, of which the following is a specification, reference being had therein to the accompanying drawings.

- 10 The invention relates to air guns of that type known as pump guns in which the compression of the spring is effected by the sliding of a handle longitudinally of the barrel. This handle is connected with a lever mechanism for actuating the movable member that compresses the spring, and one of the objects of the present invention is to obtain an improved and simplified construction in which means is provided between the lever mechanism and the spring for actuating the latter from the former with a decrease in power of the lever mechanism and an increase in rate of compression of the spring during a portion of the travel of the handle, 25 and with an increase in power of the lever mechanism and decrease in rate of compression of the spring during another portion of travel of the handle. Another object is to obtain means operated from the handle 30 guide for permitting of the passage of a projectile from the magazine into the true barrel. A further object is to obtain an arrangement of power storage and releasing mechanism which is attachable to and detachable from the stock of the gun as a unit. Still other objects of the invention reside in the means for connecting the stock to the barrel and in the novel arrangements and 35 combinations of parts as more fully herein-after set forth.

In the drawings:

Figure 1 is a sectional side elevation of the gun embodying my invention, the actuating handle being in extended position;

45 Fig. 2 is a sectional view therethrough;

Fig. 3 is a similar view showing the actuating member in retracted position;

Fig. 4 is a cross section on the line 4—4 of Fig. 2;

50 Fig. 5 is a cross section on the line 5—5 of Fig. 3.

A is the false barrel comprising the forward and rear portions A' and A² rigidly secured to each other, the rear portion A² having the depending side flanges A³. B is

the stock, C the spring located within the recess B' of the stock, D the handle movable longitudinally of the false barrel upon the handle guide D', and E is the lever mechanism connected to the handle and adapted to compress the spring C, the lever mechanism passing between the depending side flanges A³ of the false barrel. F is the true barrel axially mounted within the forward portion A' of the false barrel and having the aperture F' in its rear upper portion connecting into the magazine chamber F² which contains the projectiles. G is the cylinder within the rear portion A² of the false barrel, provided with the upwardly and downwardly extending flanges G' at its opposite ends which slidably engage the rear portion A² and are guided thereby. The cylinder G also has the axially-extending hollow tube G² at its forward end which slidably engages the true barrel F and normally closes the aperture F'. H is the plunger slidably engaging the cylinder G and connected to the detent member I through the rod H'. This detent member extends transversely of the rear portion A² of the false barrel and has the upwardly extending projection I' slidably engaging the rear portion A² and guided thereby and also has the portion I² extending between the side flanges A³ of the false barrel. The portion I² has the forward edge I³, which is substantially straight and extends at right angles to the false barrel. The detent member also has the rearwardly extending detent J adapted to be engaged by the sear J' which in turn is adapted to be actuated by the trigger K having the finger K' extending into the opening of the trigger guard L. The link M has its forward end M' bifurcated to embrace the detent member I and is pivotally connected thereto and also has the rearward end slightly curved downwardly and located in the recess M² of the abutment C' engaging in the recess B' of the stock and engaged by the spring C.

The spring C with its abutment C', the sear J' and the trigger K are inclosed within the housing N, the sear and trigger being pivoted therein. The housing also forms the trigger guard L and is detachably mounted within the recess B' of the stock B and is held in engagement therewith by means of the screw bolt O which extends through the rear portion of the stock B and threadedly

engages the spring abutment N' in the rear end of the housing. The head O' of this screw bolt is located within the recess O^2 formed in the rear end of the stock. Thus it is seen that an arrangement of power storage and releasing mechanism is provided having the one housing which is attachable to or detachable from the stock of the gun as a unit.

10 For the purpose of readily and easily connecting the stock to the false barrel, the housing N is provided with the upwardly-extending flange P at its forward end which is located within the portion A^2 of the false barrel and coöperates with the depending or downwardly extending flange P' thereon. The trigger guard L slidably engages between the side plates A^3 and is connected thereto by the screw P^2 . To withdraw the stock from 15 the barrel, the screw is removed and the stock and barrel moved relative to each other to disengage the coöperating flanges P and P' .

The lever mechanism E comprises the link 20 E' pivotally connected to the handle D at Q and the L-shaped cam member or link E^2 pivotally connected to the link E' at Q' . The opposite end of the cam member or link E^2 is pivotally connected to the rear portion 25 A^2 of the false barrel at Q^2 forward of the projection I' upon the detent member. This arrangement of link E' and cam member E^2 forms a toggle-lever which in its normal position, is extended so that the members lie 30 adjacent to the false barrel and can be broken downwardly by a rearward movement of the handle D . The legs of the L-shaped cam member or link have the cam surfaces R and R' which surfaces contact 35 with the surface I^3 of the detent member upon swinging about its pivot Q^2 the cam member or link. In the normal position, the leg having the cam surface R extends transversely of the false barrel A and in the final 40 retracted or broken position the leg having the cam surface R' extends transversely of the false barrel. The cam surface R is rounded slightly so that upon movement of the handle D toward the rear, the point of 45 contact between the cam surface R and the surface I^3 of the detent member progressively moves away from the pivot Q^2 .

In operation, to compress the spring C the handle D is moved toward the rear which 50 first breaks the toggle-lever E at which time the detent member I is but slightly moved, due to the contacting point between the cam surface R and the surface I^3 of the detent member being located relatively near to the 55 pivot Q^2 . Upon further movement of the handle D the contacting points between the cam surface R and the surface I^3 of the detent member progressively moves downward so that the leverage progressively decreases and the rate of movement of the de-

tent member I with the corresponding rate of movement of the spring C progressively increases. At this time the spring C is under small compression so that the above conditions of operation are highly desirable. 70 Upon still further movement of the handle D , the cam surface R' contacts with the surface I^3 of the detent member and the leverage increases and the rate of movement of the detent member I and also of the spring 75 C progressively decreases. At this time the spring C is under greater compression, which is also constantly increasing, so that the progressive increase of leverage is highly desirable. 80

For the purpose of admitting the projectile S into the true barrel F from the magazine chamber F^2 , the handle guide D' is slidably mounted in the strap T near the forward end of the gun and has a hooked 85 connection with the forward lower flange G' of the cylinder G . This handle guide is provided with the transversely extending pin U forward of the handle D and between the handle and the strap T . The handle guide 90 also has the upwardly-extending projection or abutment U' near its rear end and in the path of rearward travel of the pivot Q . The pin U and the projection or abutment U' are spaced from each other a sufficient distance 95 so that they are engaged by the handle D and the pivot Q , respectively, when near the ends of the forward and rearward movements of the handle. Upon rearward movement of the handle, the spring C is compressed as shown above and before the completion of the movement the pivot Q contacts with the upwardly-extending projection or abutment U' thereby moving the handle guide D' rearward which in turn 100 correspondingly moves the cylinder G with its hollow tube G^2 so that the latter opens the aperture F' in the true barrel F and permits of the passage of the projectile S from the magazine chamber into the true barrel. Upon forward movement of the handle D and near the completion thereof the handle contacts with the pin U thereby 105 moving the handle guide D' forward which in turn correspondingly moves the cylinder 110 G with its hollow tube G^2 to close the aperture F' . The forward movement of the cylinder is limited by the rear end of the forward portion A' of the false barrel. The hollow tube G^2 forces the projectile S into 115 the contracted portion of the true barrel A . The gun is now in condition to be fired by pulling the finger K' of the trigger K .

From the above description it is seen that an efficient construction of air gun is provided in which the spring for the storage of power is comparatively quickly compressed and at the same time the power is applied when most needed. Also simple means is provided for the insertion of the projectile 125 130

into the true barrel through the handle guide.

What I claim as my invention, is:

1. In a gun, the combination with a member movable for the storage of power, of a longitudinally movable actuating member, a toggle-lever operated by said actuating member, and means between said toggle-lever and power storage member for actuating the latter from the former with a decrease in power of the toggle-lever and an increase in rate of movement of the power storage member during a portion of the travel of said actuating member and with an increase 15 in power of the toggle-lever and a decrease in rate of movement of the power storage member during another portion of travel of the actuating member.

2. In a gun, the combination with a member movable for the storage of power, of a longitudinally movable actuating member, a member for moving said power storage member, a cam member having its cam surface slidably engage said last-mentioned member, and a link connecting said cam member and longitudinally movable actuating member.

3. In a gun, the combination with a member movable for the storage of power, of a longitudinally movable actuating member, a member adapted to actuate said power storage member, an L-shaped cam member having its cam surface adapted to slidably engage said last-mentioned member, and a link connecting said cam member and longitudinally movable actuating member, said cam member and link forming a toggle lever.

4. In a gun, the combination with a barrel, of a spring movable for the storage of power, a longitudinally movable handle, a member within said barrel adapted to actuate said spring, an L-shaped cam member pivoted in said barrel and having the two legs of the L adapted to contact with said member within the barrel, and a link connecting said cam member and handle, said link and cam member forming a toggle-lever.

5. In a gun, the combination with a barrel, of a spring, a handle movable longitudinally of said barrel, a cylinder within said barrel, a member within said barrel and guided thereby, adapted to actuate said spring, a plunger slidable within said barrel and connected to said last-mentioned member, an L-shaped cam member pivoted in said barrel and contacting with said last-mentioned member, and a link connecting said cam member and handle, said link and cam member forming a toggle-lever.

6. In a gun, the combination with a barrel, of a spring, a handle movable longitudinally of said barrel, a cylinder within said barrel, a detent member within said barrel,

a link between said detent member and spring, a plunger slidably engaging said cylinder and connected to said detent member, an L-shaped cam member pivoted in said barrel and contacting with said detent member, a link connecting said handle and cam member and forming with said cam member a toggle-lever, and a sear adapted to engage said detent member to hold the same in its adjusted position.

7. In a gun, the combination with a barrel having an aperture therein for the insertion of the projectile, of a longitudinally movable handle guide, means for actuating said guide, and means between said guide and barrel normally closing said aperture for opening the same upon movement of said guide.

8. In a gun, the combination with a magazine of a barrel having an aperture connecting into said magazine, a cylinder in axial alinement with said barrel, means within said cylinder for compressing air to eject the projectile in said true barrel, a handle guide movable longitudinally of said barrel, a handle upon said guide, means for actuating said handle guide from said handle, means between said handle guide and cylinder for actuating the latter, and means between said cylinder and magazine for uncovering the aperture in said true barrel upon movement of said cylinder.

9. In a gun, the combination with a barrel having an aperture therein, of a cylinder, a spring, means for compressing air in said cylinder actuated by said spring, a movable handle guide connected to said cylinder, a handle longitudinally slidably engaging said guide, means for actuating said spring and guide from said handle, and means upon said cylinder normally covering said aperture and uncovering the same upon movement of said cylinder.

10. In a gun, the combination with a false barrel, a true barrel and a projectile magazine within said false barrel, of a cylinder within said false barrel, a hollow tube connected to said cylinder and slidably engaging said true barrel, a handle guide movable longitudinally of said false barrel, a handle slidably engaging said handle guide and adapted to move the same in opposite directions, and means between said handle guide and cylinder for moving said cylinder and tube in opposite directions to permit the entrance of a projectile from said magazine into said true barrel.

11. In a gun, the combination with a false barrel, of a magazine for containing the projectile, a true barrel having an aperture therein connecting into said magazine, a cylinder within said barrel provided with a hollow rod slidably engaging said true barrel, a spring, a piston actuated by said spring and slidably engaging said cylinder,

4
a longitudinally movable handle guide, a handle longitudinally slidably engaging said handle guide, connections between said handle and spring for actuating the same to store power, connections between said handle member and handle guide for moving the latter longitudinally in opposite directions, and means between said handle guide and cylinder for correspondingly moving the latter to permit of the insertion of a projectile through said true barrel aperture.

12. In a gun, the combination with a stock having a recess therein, of a power storage and releasing unit detachably engageable in said recess, comprising a member movable for the storage of power, a trigger and a housing for said power storage member and trigger.

20 13. In a gun, the combination with a stock having a recess therein, of a unit detachably engageable within said recess, comprising a spring, a housing for said spring and a sear and a trigger pivoted in said housing, said housing forming the trigger guard.

25 14. In an air gun, the combination with a barrel having depending side plates and means for compressing air therewithin, of a stock and a member movable for the stor-

age of power located therewithin for actuating said air compressing means, said barrel having a depending flange at its upper rear end, and said stock having an upwardly-extending coöperating flange, and means for connecting the lower adjacent portions of said side plates and stock to each other.

15. In an air gun, the combination with a barrel having depending side plates and means for compressing air therewithin, of a stock, a spring within said stock for actuating said air compressing means, a housing for said spring, said housing having an upwardly-extending flange at its forward end and said barrel having a coöperating downwardly-extending flange at its rear end, and means for connecting the adjacent lower portions of said side plates and housing to each other.

50 16. In a gun, the combination with a barrel having an aperture therein for the insertion of the projectile, of a handle movable longitudinally of said barrel, a plunger within said barrel, and means normally closing said aperture, adapted to open the same upon movement of said handle in one direction and independent of said plunger.

In testimony whereof I affix my signature.
CHARLES F. LEFEVER
